GAME DEVICE SIMULATING A WESTERN
RODEO

Kenneth F. Card, Canova Park, Calif., assignor
of one-third to James L. Austin, Los Angeles,
Calif., and one-third to George F. Smyth,
Inglewood, Calif.

Application July 14, 1950, Serial No. 173,914

5 Claims. (Cl. 273—134)

1

My invention relates to equipment for playing games and in particular to playing a game simulating a championship rodeo.

As is well known, a rodeo is a competition and exhibition demonstrating the various skills of cowboys such as are employed in the cattle raising industry of the Western States in the United States. Rodeos, therefore, include events such as riding horses, not saddle broken, which try to buck off the rider, catching cattle and calves by riding them down, or riding Brahma bulls, for a minimum length of time and the equipment of the game of my invention is intended to enable players to partake in a game which simulates such rodeo events.

An object of my invention is to provide equipment for playing a rodeo game including a miniature reproduction of a typical rodeo arena and having parts arranged and operating in a manner to give the players an approximation of the interest and stimulation of participating at an actual rodeo.

A further object of my invention is to provide pieces for playing the game, of such a character as to enable pieces to be combined with others in various combinations to maintain a realistic resemblance of the course of events in a rodeo.

A still further object of my invention is to provide equipment for playing a rodeo game which is simple and inexpensive to produce, yet which is very attractive because of its accurate representation of cowboys and cow ponies, Brahma bulls, calves and other animals appearing in a rodeo and also because of its accurate reproduction of the rails with movable gates, pens for livestock and the other features of an actual rodeo, and the construction of at least some of the cowboys so that, when not in action in the game, they may be set upon the rails, which is their usual position in an actual rodeo.

Other features and advantages of the present invention will be hereinafter apparent from the following description, particularly when taken in connection with the accompanying drawings, in which

Figure 1 is a perspective view showing the game board and game pieces for playing the rodeo game of my invention set up ready for use;

Figure 2 is a plan view showing the arrangement of the playing board;

Figure 3 is a front view of a cowboy playing piece showing the piece positioned on the rails enclosing the rodeo ground;

Figure 4 is a plan view of a spinner used in playing the game;

2

Figure 5 is a side view of a cowboy playing piece mounted on one form of a piece representing the type of cow pony used in some events of a rodeo simulated in playing the game;

5 Figure 6 is a cross section on the line 6—6 of Figure 5, but showing the game pieces separated to more clearly illustrate the interengaging elements thereof; and

10 Figure 7 is a cross section on the line 7—7 of Figure 3.

The game of the present invention, referring now to the drawing and more particularly to Figure 1 thereof, comprises a board 10 upon which the component elements simulating a 15 rodeo ground are mounted, preferably removably arranged so that the game apparatus may be taken down and packed into a smaller box than would be required if the component parts are left assembled. The board 10, of course, represents the ground and the central portion thereof simulating the actual arena may be colored a tan color as the usual custom is to cover the arena with tan bark, sand or other suitable material.

25 The arena or riding area is enclosed by fence structure as in actual rodeo competitions, and the fence, in the illustrated embodiment of the invention, is comprised of posts 11 set into openings formed in the board 10 and interconnected by lower and upper rails 12 and 13, respectively. The rails are preferably made of rectangular strips of some suitable material and may be given any color desired. At one end of the arena, a starting gate 14 is arranged, and at the opposite end, an exit gate 15 is located, both gates 30 being hingedly mounted. The space outwardly of the starting gate constitutes an area known as the "chute" and is so labeled.

35 Arranged across the arena and extending between the gates 14 and 15 are a series of spaced play demarking spaces 16, here shown as horse hoof prints, arranged in a somewhat serpentine pattern. These spaces are consecutively numbered and the space numbered "5" is enclosed 40 or circumscribed by a jagged line, the purpose of which will be made clear hereinafter.

45 The "chute" in actual rodeo competition is used to confine an animal about to be ridden by a cowboy and in the game herein shown, is used in substantially the same way for it, as will be shown, is where the play for each event of the game commences. The "chute" is defined by the adjacent rails of spaced apart pens 17 and 18, which rails are similar in structure and design 50 to the rails 12 and 13 of the main arena. The

pen 17 is to be occupied during the play of the game by a game piece 19 in the form of a small replica of a calf simulating a calf which is roped and thrown in actual rodeo competition. The pen 18 is to hold a game piece 21 in the form of a Brahma bull and, as in actual rodeo competition, is ridden by game pieces representing the cowboys of the game. Adjacent the pen 17 is a similar pen 22 for holding a game piece 23 which is a replica of a horse in a bucking stance.

At the finish end of the main arena formed by the rail enclosure are two pens 24 and 25 arranged to hold, respectively, a game piece 26 in the form of a jackass and a game piece 27 in the form of a horse in a running stance. The game piece 27 is preferably given a gold color for a purpose which will be hereinafter more fully apparent.

The game includes, in addition to the game pieces above described, four identical game pieces 28, one of which is shown in Figure 5, and each consists of a small replica of a horse in a running stance. The game pieces 28 are preferably formed each of a different color so that each may be distinguished one from the other. These game pieces are to simulate the cow ponies to be ridden by the cowboy game pieces 29 during the play of the game and the game pieces 29 simulating the cowboys are preferably formed so that they can be seated on the top rail 13 or on any one of the game pieces in the form of animals ridden in a rodeo.

For this purpose the portion of the game piece corresponding to the buttocks of the cowboy may be formed with a small groove 31 to receive the top rail 13 of the main enclosure. The game piece may then be perched on the top rail in a very realistic attitude to simulate the usual position of a cowboy watching his competitors complete events in the rodeo.

To securely mount the game pieces 29 representing the cowboys to any of the game pieces simulating the animals ridden, the adjacent faces 32 of the cowboy's legs, as clearly shown in Figure 3, are planar and these faces are adapted to engage with planar walls of grooves 33 formed in the opposite surfaces of each game piece simulating an animal to be ridden by the cowboys in the play of the game. This feature is best illustrated in Figure 6 of the drawing.

The grooves 33 formed in the opposite surfaces of the game pieces simulating the animals to be ridden are quite shallow and do not detract from the realistic appearance of the game pieces and are practically invisible when the cowboy game piece is mounted thereon.

If desired, the game pieces 29 could be formed on the portion corresponding to the posterior of the figure with a small peg or the like which could be received within an opening formed in the top surface of the game pieces simulating the animals to be ridden. This peg could also be used to seat the cowboy in some desired position on the rail enclosure as, for example, by merely forming small openings in the top surface of the posts 11 which would receive the peg and hold the game piece in position.

The spinner with which the game, in its now preferred embodiment, is played is shown at 36 in Figure 4 and comprises a small board having numerals running in a double series from 1 to 4. Preferably the circle in which they are printed is in the form of a representation of a wagon wheel, while the spinner or pointer 38 which is rotatably mounted on a vertical stem is formed of a piece of suitable material twisted to repre-

sent a lariat, with a loop 39 at its end which forms the indicator as it comes to rest over a numeral when the spinner is operated.

The game of the present invention simulates a rodeo contest as it is made up of three events, namely bronc busting, calf roping, and bull riding events. Each player in turn competes in each event and each player must finish the event he is competing in before the next player takes his turn. The player who is able to complete the three events with the lowest number of points is the winner of the game and to this player goes the honor of riding the gold horse game piece 27 in the next rodeo, that is, the next series of events forming the game. The player who in each game finishes with the highest number of points is the losing cowboy, and must ride the jackass in the next "rodeo."

The game pieces are moved across the arena in accordance with the number of plays indicated after operation of the spinner and the score for each event is determined by the number of spins it takes a player to complete each event. The score for the complete game is determined by adding the points of the three events.

At the commencement of the game each player selects the game pieces representing his own cowboy and horse. In the first event, the game piece 23 which, as will be remembered, is in the form of a horse in a bucking stance, is placed in the "chute" and the first player positions his cowboy game piece on the bucking horse after which the player spins the spinner and, after opening the gate 14, moves the bucking horse and his cowboy the number of spaces 16 indicated by the spinner. The score for each player in this event is the number of spins of the spinner that the player takes to move the bucking horse with his cowboy up across the arena and out the exit gate. In the play of this event, if any player's cowboy riding the bucking horse lands on horse hoofprint numbered "5," that cowboy is thrown by the bucking horse and the event for that player ends. The score for the cowboy thrown is determined by adding three points to the number of spins of the spinner previously taken by that player.

In the second or calf roping event, the game piece 19 representing the calf is taken from the pen 17 and placed in the "chute" just in front of the cowboy game piece 29 which is now mounted on the game piece 28 or cowpony game piece. The player now spins the spinner and moves the calf the number of spaces or prints 16 indicated by the spinner. This player then again spins the spinner and moves his horse and cowboy the number of spaces shown by the spinner. The spinner is repeatedly spun by the same player to first move the calf and then his horse and cowboy until his horse and cowboy catches up with or passes the calf. The event is over for each player if his horse and cowboy catches or passes the calf before the calf is moved out of the arena. If a player's horse and cowboy does not catch or pass the calf before the calf moves out of the arena, that player spins the spinner until his horse and cowboy are moved across and out of the arena. Points for that player are scored by adding to the number of spins taken to move the horse and cowboy across the arena a penalty of five points. If the losing cowboy of the previous game riding the jackass in this event does not overtake or pass the calf before the calf is moved out of the arena, he must add to his score a penalty of ten points. If the losing cowboy riding the jackass catches or passes the calf,

he subtracts one point from his score of this event.

In the third event, which is the Brahma bull riding event, the play of the game is exactly the same as that of the bronc riding event. The play of this event will, therefore, not be again described.

It will be seen now that the game of this invention does simulate in practically all details an actual rodeo competition. The game has been to be attractive to adults as well as children and in addition to the game aspects thereof, it serves as a very entertaining toy to children too young to appreciate the play of the game.

Although the now preferred embodiment of the present invention has been shown and described herein, it is to be understood that the invention is not to be limited thereto, for it is susceptible to changes in form and detail within the scope of the appended claims. Thus, for example, all game pieces could be formed as substantially flat elements of cardboard or other suitable material in the form of silhouettes of cowboys and animals rather than molded pieces of a plastic, and yet retain all of the features of the game pieces as herein shown and described.

I claim:

1. Apparatus for playing a game simulating a rodeo, comprising: a substantially rectangular board; a plurality of post-like members vertically projecting from one surface of said board; a plurality of rail-like members horizontally interconnecting said post-like members to form an elongate railed enclosure on said board representing a rodeo arena; a plurality of play demarking areas spacedly arranged across said arena; at least a pair of spaced apart railed pens at each end of said arena, said pens defining a starting chute at one end of said enclosure and an exit passage at the opposite end; a plurality of game pieces in the form of cowboys; means on said game pieces so constructed and arranged as to interengage with said railed enclosure to mount said game pieces thereon during the play of said game; a plurality of game pieces in the form of animals ridden by cowboys in a rodeo; and means on said game pieces in the form of animals ridden by cowboys in a rodeo for interengaging with means carried by the game pieces in the form of cowboys to detachably hold the latter on said animal game pieces, whereby a cowboy game piece and a game piece simulating an animal ridden may be moved from one play demarking area to another as a unitary game piece.

2. Apparatus for playing a game simulating a rodeo, comprising: a substantially rectangular board; a plurality of post-like members vertically projecting from one surface of said board; a plurality of rail-like members horizontally interconnecting said post-like members to define a railed enclosure on said board open at both ends thereof; a plurality of play demarking areas spacedly arranged across said enclosure and leading from one opening to the other; a plurality of game pieces in the form of cowboys; means on said game pieces so constructed and arranged as to interengage with the upper rail-like member of said enclosure to mount said game pieces thereon; a plurality of game pieces in the form of animals ridden by cowboys in a rodeo; and means on said game pieces in the form of animals ridden by cowboys in a rodeo for interengaging with means carried by the game

pieces in the form of cowboys to hold the latter on said animal game pieces against accidental separation, whereby a cowboy game piece and a game piece simulating an animal ridden may be moved from one play demarking area to another as a unitary game piece.

3. Apparatus as set forth in claim 2 and in which the inner sides of the legs of the cowboy game pieces are formed as substantially parallel planar surfaces at least for a portion of their length, and the opposite sides of the game pieces simulating animals ridden are each formed with grooves having a planar wall, said grooves receiving the legs of the cowboy game pieces with the planar surfaces thereof in facewise engagement with planar wall surfaces of the grooves.

4. Apparatus for playing a rodeo game, comprising: a board; posts and rails defining an elongated enclosure positioned on said board representing a rodeo arena; railed pens spaced apart at one end of the enclosure defining a starting chute; railed pens spaced apart at the end of the arena opposite the starting chute defining an exit passage; a plurality of game pieces in the figures of cowboys, at least some of which are formed in sitting position with knees spread apart, a slot being provided across the seat of the cowboy which is adapted to receive the top rail of the enclosure and support the cowboy thereon in sitting position, and a plurality of game pieces in the figures of horses; the legs of the cowboy game pieces being adapted to interfit with said last named game pieces, said board being marked at a plurality of points with numbered positions, the numbers increasing from the chute to the exit passage and demarking play areas across which a cowboy game piece interfittingly engaged with a horse game piece may be moved as a unitary piece.

5. Apparatus for playing a game simulating a rodeo, comprising: a substantially rectangular board; a plurality of post-like members vertically projecting from one surface of said board; a plurality of rail-like members horizontally interconnecting said post-like members to define a railed enclosure on said board representing a rodeo arena; a plurality of play demarking areas arranged across said enclosure; a plurality of game pieces in the form of cowboys; cooperating means on said game pieces and said railed enclosure for mounting said game pieces on the latter; a plurality of game pieces in the form of animals ridden by cowboys in a rodeo; and cooperating means on said animal game pieces and the game pieces in the form of cowboys for mounting the latter on said animal game pieces to simulate a cowboy astride an animal, whereby a cowboy game piece and a game piece simulating an animal ridden may be moved from one play demarking area to another as a unitary game piece.
